UNITED STATES PATENT OFFICE.

JOSEPH E. LEMYRE, OF MANCHESTER, NEW HAMPSHIRE.

BOBBIN FOR COTTON-LOOMS.

No. 879,278.

Specification of Letters Patent.

Patented Feb. 18, 1908.

Application filed March 9, 1907. Serial No. 361,490.

To all whom it may concern:

Be it known that I, JOSEPH E. LEMYRE, a citizen of the United States, residing in Manchester, in the county of Hillsboro and State 5 of New Hampshire, have invented a new and useful Improvement in Bobbins for Cotton-Looms, of which the following is a specification.

This invention relates particularly to bobbins of the style provided with a filling change, and more specifically to bobbins which are provided with a sleeve or tube on the spindle, which is held in position by the thread until but little thread is left on the 15 spindle, when said sleeve moves from its position and allows the bobbin to be drawn off, a bobbin provided with a sleeve or cone of this general character being illustrated in Letters Patent of the United States No. 20 788,806, granted May 2, 1905.

In the Letters Patent referred to, the sleeve or tube (termed a "cone" in said Letters Patent) is connected with the spindle by means of ears or projections which extend 25 from the inner end of the sleeve into longitudinal slots in the spindle, said ears bending substantially from their extreme rear ends—the ends which join the tube—diagonally or at obtuse angles into the slots. It has been 30 found in practice that in tubes or sleeves, whether conical or with parallel sides, provided with ears of this shape, the thread is frequently pinched against or under the inner end or edge of the tube and is thus broken.

35 My invention has for its principal object to obviate this difficulty by preventing the thread at or about the time when the sleeve is being released by the unwinding of the thread from coming in contact with the said 40 end or edge of the sleeve, the thread being prevented or guarded from or against such contact by the shape of the ears or projections themselves. As the improved ears send off the thread from the adjacent end or 45 edge of the tube, pinching and consequent breaking of the thread is prevented.

The nature of the invention is fully described below, and illustrated in the accompanying drawings, in which—

50 Figure 1 is a view of a spindle with my improved sleeve in position thereon, the thread being nearly unwound from the bobbin, and that which is left on the spindle being guarded or fended off from contact with the tube 55 by the ears or projections which extend into the slots in the spindle. Fig. 2 is a longitu-

dinal section of a portion of the spindle with the ears in the same position as in Fig. 1. Fig. 3 is a view in perspective of the sleeve removed.

60

Similar letters of reference indicate corresponding parts.

a represents the spindle, and *b* the head thereof, said spindle being provided with the opposite longitudinal slots *c*. On the portion *d* of the spindle between the slots and the head is a loose tube or sleeve *e*, preferably of substantially even diameter throughout its length, the rear outer end of the sleeve being formed up into an annular flange *f*, 70 which may be engaged by any suitable mechanism which is exposed to the direct blows of the feeler. The inner end of the tube *e* is provided with two ears or projections, which are opposite each other and extend into the slots *c*. Each of these ears is integral with the sleeve, and consists of the broad portion *g*, which is in a straight line with the portion of the side of the tube from which it extends and the portion *h* which 75 bends inward at substantially right angles with the portion *g* into the slot *c*. The portion *h* is comparatively narrow and the edges of the portion *g* broaden regularly, as shown from the portion *h* to the body of the tube. 80

85

In practical operation, when the thread is nearly unwound, and the sleeve is loosened in its position, said sleeve is checked in its approach toward the thread by the ears, and the thread comes in contact only with the 90 portions *h* of said ears, being held off from the adjacent edge or end of the sleeve by the portion *g* of the ears, said portion *g* being long enough to prevent any possibility of the thread being reached and pinched by the 95 sleeve and thus broken. The width of the portion *g* is sufficient to insure strength to prevent said portion from bending, and as the portion *g* is bent inward at right angles there is no danger of the thread riding up 100 onto said portion.

I do not, of course, limit myself to the number of ears and corresponding slots, as there may be either one or more of said ears employed.

105

Having thus fully described my invention what I claim and desire to secure by Letters Patent, is—

110 1. A bobbin of the character described comprising a spindle provided with a suitable head and with a longitudinal slot near said head; a sleeve on said spindle between the

slot and the head; and an ear or projection extending from the inner end of the sleeve in a straight longitudinal line for an appreciable distance from the said end of the sleeve and 5 thence bending inward into the slot, for the purpose set forth.

2. A bobbin of the character described comprising, a spindle provided with a suitable head and with a longitudinal slot near said 10 head; a sleeve on said spindle between the slot and the head; and an ear or projection extending from the inner end of the sleeve in a straight longitudinal line for an appreciable distance from the said end of the sleeve 15 and thence bending inward at substantially right angles into the slot, whereby a shoulder is provided at a distance from the sleeve for keeping the thread when it is nearly unwound from contact therewith.

3. A bobbin of the character described 20 comprising, a spindle provided with a suitable head and with a longitudinal slot near said head; a sleeve on said spindle between the slot and the head; and an ear or projection extending from the inner end of the sleeve 25 in a straight longitudinal line for an appreciable distance from the said end of the sleeve and thence bending inward into the slot, the longitudinal portion of the ear connecting the inturned ends with the sleeve being comparatively broad, for the purpose set forth.

In testimony whereof I have signed my name to this specification in the presence of two subscribing witnesses.

JOSEPH E. LEMYRE.
